DESIGN FOR A BOOK COVER

Cyril von Baumann, New York, N. Y.

Application June 21, 1946, Serial No. 130,917

Term of patent 3½ years

(Cl. D6—2)

To all whom it may concern:

Be it known that I, Cyril von Baumann, a citizen of the United States, resident of the city, county, and State of New York, have invented a new, original and ornamental Design for a Book Cover, of which the following is a specification, reference being made to the accompanying drawing, showing part thereof.

Fig. 1 is a front perspective view of a book cover, showing my new design, the back of same being plain but conforming to the outline of the front.

Fig. 2 is a front perspective view of the cover with the child removed therefrom; and

Fig. 3 is a front elevational view of the child

figure, the back thereof being plain but conforming to the outline of the front.

I claim:

The ornamental design of a book cover, as shown and described.

CYRIL VON BAUMANN.
